CONTAINER AND CAP THEREFOR

Frederic H. Jobson, Atlanta, Ga.

Application December 28, 1950, Serial No. 203,049

8 Claims. (Cl. 222—505)

1

This invention relates to a container, and more particularly to a container of the type commonly referred to as a collapsible tube, such as is employed for containing tooth paste, shaving cream or the like.

The primary object of the invention is to avoid the loss of the closure cap for the container and to assure its association at all times with the container for ready movement into and out of closing relation with the discharge opening of the container.

Another object is to move the closure cap into and out of closing relation with the discharge opening of the container by the simple movement of an element of the device in a rectilinear path across the discharge end of the container.

Still another object is to facilitate the rapid assembly of the closure cap with the container and the actuating slide member.

The above and other objects may be attained by employing this invention which embodies among its features a closure cap carried by the container for movement in a curved path into and out of closing relation with the discharge opening of the container, a slide member carried by the container for movement in a path which intersects the curved path, means carried by the slide member for movement into intersecting relation with the curved path and engagement with the closure cap to hold said closure cap in closing relation with the discharge opening of the container, and means carried by the closure cap and engageable by the slide member for moving said closure cap out of discharge opening closing relation upon movement of the closure cap retaining means out of the arcuate path.

In the drawings:

Figure 1 is a fragmentary edge view of a container and closure cap embodying the features of this invention;

Figure 2 is a fragmentary sectional view through a container illustrating this improved closure cap and slide member in place thereon, with the closure cap in closing relation to the discharge opening of the container;

Figure 3 is a view similar to Figure 2 illustrating the slide member retracted and the closure cap moved to open position;

Figure 4 is a view similar to Figures 2 and 3 illustrating the parts in another position;

Figure 5 is a view similar to Figures 2 and 3 illustrating the manner of assembling the parts; and

Figure 6 is a perspective view of the closure cap and actuating arm and lugs therefor.

2

Referring to the drawings in detail a conventional collapsible tube 10 is provided at one end with a head 10a having therethrough a discharge throat 12 adjacent which is formed in the head 5 a chamber 14. The chamber 14 opens outwardly adjacent the discharge end of the throat 12 through the top surface 12a and the top edge of the wall of the chamber remote from the throat 12 is provided with a notch 16 the purpose of which 10 will hereinafter appear. As illustrated in the drawings, the discharge end of the throat 12 is inclined toward the body of the container 10 as it recedes from the longitudinal axis of the container to form an inclined seat 18 for engagement 15 by the closure cap to be more fully hereinafter described. The container is provided on opposite sides of the throat 12 and chamber with dovetail grooves 22 (Fig. 1), and at opposite ends with transversely extending grooves 24 and 26.

20 A closure cap 28 is provided at one end with a perpendicular flange 30 for entrance into the groove 26 and carried by the opposite end of the closure cap 28 is an actuating arm designated generally 36 which is received in the chamber 14 as will be readily understood upon reference to the drawings. A layer of suitable sealing material 38 is carried by the cap 28 between the flange 30 and the arm 36 for engagement with the inclined end 18 of the discharge throat 12 25 in order to form a tight seal therewith when the cap is in closed position. The end of the arm 36 adjacent the cap 28 is made relatively heavy and extends at an obtuse angle relative to the cap. As the arm recedes from the angular extension it curves in the direction of the plane of the top of the cap and is provided at its end remote from the cap with a fulcrum lug 40 which is adapted to enter the notch 16 previously referred to and form a pivot about which the cap 30 moves in a curved path away from the throat 12. An actuating lug 42 is carried by the arm 36 at the end thereof remote from the cap 28 and projects in a direction opposite the lug 40 as will 35 be readily understood upon reference to the drawings.

40 Mounted for sliding movement on the container head 10a in the dovetail grooves 22 thereof is a slide member designated generally 44 and provided adjacent one end with a recess 46 which 45 opens toward the container 10 and is provided with a cam wall 48 which is adapted to engage the lug 42 as the slide member 44 moves in a rectilinear path which intersects the path of movement of the closure cap 28. Carried by the 50 slide member 44 adjacent the end thereof remote

from the recess 46 is a closure cap retaining member 50 which is moved with the slide member into and out of intersecting relation with the curved path in which the closure cap 28 is moved into and out of sealing relation with the seat 18 of the discharge throat 12. As illustrated, the cam 48 is so located and shaped that as the slide member 44 is moved to retract the closure cap retaining means out of intersecting relation with the curved path of movement of the closure cap, the actuating lug 42 of the actuating arm 36 is moved downwardly to place the arm 36 under tension and seat the fulcrum lug 40 in the notch 16. Substantially upon the instant of withdrawal of the closure cap retaining means from its projection into the path of movement of the closure cap, the cam 48 contacting the actuating lug 42 will cause said lug to rock about the fulcrum lug 40 in the notch 16 and move the closure cap out of closing relation with the seat 18, thus exposing the discharge opening in the throat 12 to permit the contents of the container 10 to be dispensed through said opening.

When the desired amount of material has been removed from the container 10, the slide member 44 is moved to advance the closure cap retaining means toward the curved path of movement of the closure cap, thus permitting the weighted end of the arm 36 to move into the chamber 14 substantially as illustrated in Figure 3 and upon further movement of the slide member 44, the closure cap retaining means will be advanced into intersecting relation with the curved path and contact with the closure cap to force it into sealing relation with the seat 18.

In assembling the parts, the lug 40 is seated in the recess or notch 16 with the actuating arm 36 lying substantially parallel with the end of the container 10. The slide member 44 is then engaged with the dovetail grooves 22 and advanced across the actuating lug 42 toward the throat 12 and in end closing relation with the chamber 14. Obviously as the closure cap retaining means moves into closure cap retaining position, the arm 36 will rock about its fulcrum 40 into substantially the position illustrated in Figure 2.

By thus moving the slide member, the closure cap retaining means 50 is advanced into and out of intersecting relation with the curved path through which the closure cap 28 moves and when said closure cap retaining means lies in intersecting relation with said path, the closure cap 28 will be held in sealing relation with the seat 18 of the throat 12.

In the preferred form of this invention the arm 36 is made of a resilient material so that the cam 48 can place the arm under tension and the instant that the closure cap retaining means 50 moves out of the curved path, the closure cap 28 will spring upwardly away from the seat 18 to break the seal therewith.

While in the foregoing there has been shown and described the preferred form of this invention, it is to be understood that minor changes in the details of construction, combination and arrangement of parts may be resorted to without departing from the spirit and scope of the invention as claimed.

I claim:

1. In a container having a discharge opening communicating with the interior thereof, a closure cap carried by the container for movement in a curved path into and out of sealing relation with said discharge opening, a slide member

mounted on the container for movement in a path which intersects the curved path, an actuating arm carried by the closure cap, a fulcrum lug carried by the actuating arm for engagement with the container, an actuating lug carried by the arm and projecting into the path of movement of the slide member, and means on the slide member for engaging the actuating lug and moving the arm to move the sealing cap out of sealing relation with the discharge opening as the slide member moves out of the curved path.

2. In a container having a discharge opening communicating with the interior thereof, a closure cap carried by the container for movement in a curved path into and out of sealing relation with said discharge opening, a slide member mounted on the container for movement in a path which intersects the curved path, closure cap retaining means on the slide member and movable therewith into and out of the curved path for engaging the closure cap and holding it in sealing relation with the discharge opening, an actuating arm carried by the closure cap, a fulcrum lug carried by the actuating arm for engagement with the container, an actuating lug carried by the arm and projecting into the path of movement of the slide member, and means on the slide member for engaging the actuating lug and moving the arm to move the closure cap out of sealing relation with the discharge opening when the closure cap retaining means moves out of the curved path.

3. In a container having a discharge opening communicating with the interior thereof and a notch in spaced relation to the discharge opening, a closure cap carried by the container for movement in a curved path into and out of sealing relation with said discharge opening, a slide member mounted on the container for movement in a path which intersects the curved path, an actuating arm carried by the closure cap, a fulcrum lug carried by the actuating arm for entrance into the notch, an actuating lug on the arm projecting into the path of movement of the slide member, and means carried by the slide member for engaging the actuating lug and advancing the fulcrum lug into the notch and subsequently rocking the arm to move the closure cap out of sealing relation with the discharge opening.

4. In a container having a discharge opening communicating with the interior thereof and a notch in spaced relation to the discharge opening, a closure cap carried by the container for movement in a curved path into and out of sealing relation with said discharge opening, a slide member mounted on the container for movement in a path which intersects the curved path, an actuating arm carried by the closure cap, a fulcrum lug carried by the actuating arm for entrance into the notch, an actuating lug on the arm projecting into the path of movement of the slide member, means carried by the slide member for engaging the actuating lug and advancing the fulcrum lug into the notch and subsequently rocking the arm to move the closure cap out of sealing relation with the discharge opening, and closure cap retaining means carried by the slide member and movable therewith into intersecting relation to the curved path for engaging the closure cap and holding it in closing relation with the discharge opening.

5. In a container having a discharge opening communicating with the interior thereof and a notch in spaced relation to the discharge open-

ing, a closure cap carried by the container for movement in a curved path into and out of sealing relation with said discharge opening, a slide member mounted on the container for movement in a path which intersects the curved path, an actuating arm carried by the closure cap, a fulcrum lug carried by the actuating arm for entrance into the notch, an actuating lug on the arm projecting into the path of movement of the slide member, and a cam surface on the slide member for engaging the actuating lug to move the fulcrum lug into the notch and subsequently rock the arm about the fulcrum lug to move the closure cap in the curved path out of sealing relation with the discharge opening.

6. In a container having a discharge opening communicating with the interior thereof and a notch in spaced relation to the discharge opening, a closure cap carried by the container for movement in a curved path into and out of sealing relation with said discharge opening, a slide member mounted on the container for movement in a path which intersects the curved path, an actuating arm carried by the closure cap, a fulcrum lug carried by the actuating arm for entrance into the notch, an actuating lug on the arm projecting into the path of movement of the slide member, a cam surface on the slide member for engaging the actuating lug to move the fulcrum lug into the notch and subsequently rock the arm about the fulcrum lug to move the closure cap in the curved path out of sealing relation with the discharge opening, and closure cap retaining means carried by the slide member for movement therewith into intersecting relation with the curved path and engagement with the closure cap to hold said cap in sealing relation with the discharge opening.

7. In a container having a discharge opening communicating with the interior thereof, a closure cap supported by the container for rocking movement only in a curved path into and out of sealing relation with said discharge opening, said cap including an actuating arm, a slide

member mounted on the container for rectilinear movement in a path which intersects the curved path, and closure cap retaining means on the slide member and movable therewith into and out of the curved path and having a sliding camming engagement with the closure cap arm for rocking and holding the cap in sealing relation with the discharge opening.

8. In a receptacle of the character stated having a head, the head having a relatively long top surface and a discharge throat opening through said surface, a finger actuated cap slidably supported for movement longitudinally of said surface for covering and uncovering said throat opening, a sealing plate designed to be interposed between the cap and said opening to close the opening, an actuating arm connected at one end to the plate and extending lengthwise of said surface, an actuating lug formed at the other end of said arm remote from said throat opening, a fulcrum coupling between said other end of the arm and the head on which the arm swings, the cap having a recess at one end for receiving and releasably holding said lug to maintain the cap in closed position over the mouth, a portion of the underside of the cap forming a retaining member for engaging the plate upon sliding movement of the cap in one direction, and means upon the underside of the cap for camming engagement against the lug to effect and limit the opening movement of the cap.
